FIG.1

FIG.2

FIG.3

FIG. 4

FIG. 1 is a side elevational view showing a container unit for motorcycles and the like showing my new design, it being understood that the opposite side is a mirror image thereof;

FIG. 2 is a top plan view thereof;

FIG. 3 is a rear elevational view thereof; and

FIG. 4 is a front elevational view thereof.

The broken line showing of the motorcycle, tail lights, and latch locks is for illustrative purposes only.

The undisclosed bottom portions of the container unit for motorcycles and the like are substantially flat and unornamented.

I claim:

The ornamental design for a container unit for motorcycles and the like, as shown and described.
